UNITED STATES PATENT OFFICE

2,557,048

BOX TYPE HINGE

Lawrence H. Haase, Evansville, Ind., assignor to
Kent Plastics Corporation, Evansville, Ind.

Application October 12, 1948, Serial No. 54,015

8 Claims. (Cl. 220—31)

1

The invention relates to jewel box structures and the like and more particularly to the hinging employed between the box and cover.

The chief object of this invention is to hingedly connect the two parts aforesaid in such a manner that the cover is held open in an "over center" position and is held in closed position, when desired, the hinging being of self closing character.

The chief feature of the present invention resides in the particular formation of the adjacent portions of the box and cover, and the novel association therewith of a coil spring of peculiar shape and a rigid hinge pin or pintle or a resilient pintle. In other words for the majority of box structures but two pins and two springs or two resilient pintles are required and when the box is closed only the remote ends of such pins are exteriorly exposed, the springs if used being concealed.

Other objects and features of the invention will be set forth more fully in detail hereinafter.

The full nature of the invention will be understood from the accompanying drawings and the following description and claims:

In the drawings Fig. 1 is a perspective view of a closed box structure embodying the invention with the included spring.

Fig. 2 is a transverse sectional view through the same, the cover being shown in "over center," self sustaining open position.

Fig. 3 is a perspective view on an enlarged scale of the hinge formation of this invention, the view being taken looking into the structure with the cover in open position.

Fig. 4 is a perspective view on a still larger scale of one of the springs embodied in the invention.

Fig. 5 is an enlarged sectional view of a second embodiment of the invention and one without a spring.

Fig. 6 is a similar view of a third embodiment, same also being of springless character.

In Fig. 1 of the drawings 10 indicates a box having the back wall 11 and end walls 12. The cover 13 includes back wall 14. Projecting therefrom and in coplanar alignment are the projections or tongues 15. The box back wall in its confronting face includes tongue receiving notches 16. Herein a cooperating pair of the aforesaid is disposed adjacent the ends of the box.

A pin 17 serving as a connector and hinge pin passes through hole 18 opening upon the end 12 at 19. An aligned hole 20 is formed in the tongue

15. In the back 11 across the slot may be an

2

aligned hole if desired. In this event the pin is longer than that illustrated herein. When a short pin is utilized holes 20 do not extend through the tongues but terminate at 20a.

5 Between the tongue seating notch and end wall 12 and in back wall 11 is an inwardly and upwardly opening recess 22, the back wall portion 23 of which is slightly notched as at 24 for a purpose now to be described.

10 The spring 25, see Fig. 4, has at one end a short extension 26 terminating in free end portion 27 and at the other end has longer extension 28 terminating in free end portion 29. These portions are directed inwardly and are parallel and 15 may partially lap. The arms when the cover is open are disposed at approximately 80°, plus or minus 5°, to each other.

The bottom wall of recess 23 includes slot 30 herein shown coextensive with the length of recess 23. This slot seats spring end 27. The confronting edge of cover back wall 14 is similarly recessed at 31 to seat spring end 29. Arm 28 is disposed in notch 24 when the cover is in open position.

25 The spring 25 is nested at all times in recess 22. The hinge pin 17 extends entirely through the spring 25. Note that the free end of tongue 15 is curved as at 15a so as to clear the bottom wall of notch 16 when the cover is opened. The flat back of tongue 15 bears on this bottom wall when

30 the cover is opened and prevents further opening movement of the cover. Obviously a right and a left hand spring must be utilized in a two hinge structure. Note also the slight gap between back walls 11 and 14 when the box is closed. This facilitates box opening and prevents cover binding.

35 In Fig. 5 there is illustrated a modified form of the invention. Herein numerals of the 100 series indicate parts like or similar to those shown in Figs. 1 to 5 and indicated by the primary numerals.

The box again is notched to receive the cover tongues. The pintle 117 herein extends through tongue 115 and is secured at opposite sides of the notch to the box member.

40 Herein tongue 115 includes a projection 115a. Notch 116 includes extension 116a. The box back wall 111 includes closure portion 111a and ledge 116b. The pintle 117 is of semi-rigid resilient stock and yields laterally when required. It is so disposed in the tongue that when the cover is closed or opened it yields for extension movement.

45 55 When the cover is open it is held in this posi-

tion by portion 115a bearing upon ledge 116b. When the cover is closed it is so held by portion 115a seating in notch extension 116a.

In Fig. 6 numerals of the 200 series are utilized. Herein tongue 215 includes a step cam portion 215a with step 215b. Box member 210 has its notch 216 closed as at 211a and provided with cam surface 216a and ledge 216b. Pintle 217 again is eccentrically disposed as it were. This form operates like that shown in Fig. 5.

The spring accommodating notches may be utilized or omitted and if present springs may be utilized in either Fig. 4 or Fig. 5 form as previously set forth for the Figs. 1 to 4 form. In the last two forms the pintles preferably extend across the notch but need not do so in all cases. Also in the form Figs. 1 to 3, the pintles 17 may extend across the notch and be box anchored at opposite ends.

While the invention has been illustrated and described in great detail in the drawings and foregoing description, the same is to be considered as illustrative and not restrictive in character.

The several modifications described herein as well as others which will readily suggest themselves to persons skilled in this art, all are considered to be within the broad scope of the invention, reference being had to the appended claims.

The invention claimed is:

1. In a box structure having a box member and a cover member, the combination with a plurality of tongues depending from the one member toward the other when in box formation, the other member having complementary tongue receiving notches in its tongue confronting portion, hinge pintle means carried by the notched member and extending across the notches and into the tongues, and means resiliently constraining said members to maintain the cover in closed position, said last mentioned means being disposed in the notches and supported by said pintle means.

2. A structure as defined by claim 1 wherein the notches have ledge portions and the tongues include offsets for ledge portion engagement.

3. A structure as defined by claim 1 wherein each notch has a surface non-concentric with respect to the axis of said pintle means and portions upon the said tongue having cooperating engagement with the aforesaid surface.

4. In a box structure having a box member and a cover member the combination therewith of a hinge pin and a pin enveloping spring, one of said members having a tongue projecting toward the other of said members, the said other member having in its confronting portion a notch to receive said tongue the notch and tongue having arcuate complementary confronting portions, the pin extending from the said other member

adjacent the notch therein and into said tongue, the said other member in juxtaposition to the notch, having a spring nesting recess therein, opposite ends of said spring being secured to the said members.

5. A box structure as defined by claim 4 wherein the spring is of coiled type with lateral arms at the ends thereof, each arm having a free end disposed angularly of the arm and directed toward the other free end, the ends being approximately parallel to each other and parallel to the axis of the spring, each member having a longitudinally disposed recess in juxtaposition to the first mentioned recess to seat the spring free end, said last mentioned recesses substantially confronting each other and communicating with the first mentioned recess when the box is closed.

10 6. A box structure as defined by claim 4 wherein the said other member includes a spring 20 accommodating notch therein disposed transversely of the first mentioned notch and communicating therewith.

15 7. A box structure as defined by claim 4 wherein the recess and notch of said other member are longitudinally aligned and have end to end communication with each other, said other member having a second notch which simultaneously communicates with the recess and first mentioned notch and is directed transversely thereof.

20 8. A box structure as defined by claim 7 wherein the spring is of coiled type with lateral arms at the ends thereof, each arm having a free end disposed angularly of the arm and directed toward the other free end, the ends being approximately parallel to each other and parallel to the axis of the spring, each member having a longitudinally disposed recess in juxtaposition to the first mentioned recess to seat the spring free end, said last mentioned recesses substantially confronting each other and communicating with the first mentioned recess when the box is closed.
